US0D1108047S

(12) **United States Design Patent** (10) **Patent No.:** **US D1,108,047 S**
(45) **Date of Patent:** **** Dec. 30, 2025**

(54) **DRYER FOR CLOTHING**

(71) Applicant: **LG Electronics Inc.**, Seoul (KR)

(72) Inventors: **Kihyuk Kim**, Seoul (KR); **Bohyun Nam**, Seoul (KR); **Hoil Jeon**, Seoul (KR); **Seunghyun Song**, Seoul (KR); **Junseop Lee**, Seoul (KR)

(73) Assignee: **LG ELECTRONICS INC.**, Seoul (KR)

(**) Term: **15 Years**

(21) Appl. No.: **35/522,147**

(22) Filed: **Aug. 24, 2023**

(80) **Hague Agreement Data**

Int. Filing Date: **Aug. 24, 2023**

Int. Reg. No.: **DM/232398**

Int. Reg. Date: **Aug. 24, 2023**

Int. Reg. Pub. Date: **Aug. 30, 2024**

(30) **Foreign Application Priority Data**

Feb. 24, 2023 (KR) 30-2023-0007168

(51) **LOC (15) Cl.** **15-05**

(52) **U.S. Cl.**

USPC **D32/8**
